UNITED STATES PATENT OFFICE.

CARL HENDERSON, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

SHEET-REGISTERING MECHANISM.

1,367,257.

Specification of Letters Patent.

Patented Feb. 1, 1921.

Application filed May 4, 1917. Serial No. 186,295.

To all whom it may concern:

Be it known that I, CARL HENDERSON, a citizen of the United States, residing at Oak Park, in the county of Cook and State of Illinois, have invented certain new and useful Improvements in Sheet-Registering Mechanism, of which the following is a specification.

This invention relates to sheet registering mechanism for printing presses of that type in which substantially fixed guides are employed for effecting front and side register of the sheets.

The main and primary object of the invention is the provision of registering mechanism the parts of which are so coördinated and organized as to insure greater accuracy of register notwithstanding the necessity of overcoming the inertia of the sheet by the rapidly-rotating impression cylinder of the machine at the time of engagement of its grippers with the sheet.

The invention also aims to provide registering mechanism the actuation of which is controlled by the sheet itself and dependent upon the accurate registering of the sheet, thereby preventing feeding of the sheets to the impression cylinder until the accurate positioning of the sheets has been accomplished.

A further object of the invention is the provision of simple and efficient means for retaining the sheet in position after it has been brought into register, and while so held to present the front edge thereof to the bite of the grippers. The passage of the sheet to the impression cylinder without disturbance of its registered position is thus insured.

Other objects and advantages of the invention will be apparent as the nature of the improvements is better understood, the invention consisting substantially in the novel construction, combination and arrangement of parts hereinafter fully described, illustrated in the accompanying drawings, and finally pointed out in the appended claims. It will be understood, however, that the structure illustrated and described is but a schematic adaptation of the invention, and that the latter is susceptible of embodiment in other forms, so that the invention is not to be limited to the particular embodiment shown and described.

In the drawings—

Figure 1 is a diagrammatic view in eleva-

tion of sheet registering mechanism constructed in accordance with and embodying the principles of the present invention;

Fig. 2 is a top plan view of the structure illustrated in Fig. 1;

Fig. 3 is a sectional plan view, on an enlarged scale, of the feed table and its adjuncts;

Fig. 4 is a longitudinal sectional view of the structure illustrated in Fig. 3, together with the parts above the plane of the section on which Fig. 3 is taken;

Fig. 5 is a fragmentary sectional elevation on the line 5—5 of Fig. 4; and

Fig. 6 is a diagrammatic view of the electrical circuits for certain of the instrumentalities included in the sheet registering mechanism.

Referring now in detail to the accompanying drawings, the numeral 10 designates the impression cylinder of a printing couple to which the sheets are fed in regular succession from a stack 11. Automatic means are conventionally illustrated for this purpose, the same including a plurality of suction feed belts 12 designed to pick up the sheets individually from the stack 11 and advance the same toward the impression cylinder 10, the sheets passing over a guide 13 in proximity to which is arranged a suction feed roll 14 of known construction. In advance of the suction feed roll 14 is arranged a plurality of feed rolls 15, said rolls being disposed at a slight angle to the line of travel of the sheet and thus adapted to impart to the sheet a side-wise movement, whereby the same is brought into contact with a side gage 16 adjustably mounted above the peripheries of the rolls 15.

By means of the gage 16 a preliminary side register is given to the sheet, and as the sheets are advanced by the rolls 15 they contact with a transversely extending stop 17 which retards the forward movement of each sheet until the same is engaged by gripper mechanism 18 carried by a plurality of endless belts 19 operating over pulleys 20 of suitable construction. The stop 17 is guided for vertical movement and is timed to move out of the way of the sheet through the medium of Geneva gears 21 and toggle connections 22 between said gears and the stop 17, and said stop is returned to its normal position across the path of the sheet by means of a spring 23. The normal position of the

toggle is fixed by the stud 23^a. As the sheet is advanced by the gripper mechanism 18 its trailing end is caught by a supporting table 24 in advance of which is arranged a 5 suction feed roll 25. This roll is also of known construction. When the sheet is released by the grippers 18 it is deposited on a feed table 26, the sheet being moved forwardly over said table by the feed roll 25, 10 and from the feed table 26 the sheet is delivered to the impression cylinder 10 in a manner hereinafter described.

Associated with the feed table 26 are the instrumentalities for effecting both front 15 and side final register of the sheet. These include a plurality of front guides 27 and a side guide 28, said guides being mounted for vertical movement to permit feeding of the sheet to the impression roll 10. To effect 20 proper front register it is, of course, necessary that the front edge of the sheet shall contact with the guides 27, and to this end a plurality of feed dogs 29 are employed, said dogs coöperating with a plurality of feed 25 shoes 30. The dogs 29 engage the upper surface of the paper while the shoes 30 contact the lower face of the sheet. One of the dogs 29 is arranged above each of the shoes 30, each dog being mounted on an eccentric 31, 30 and a similar eccentric 32 is provided for each of the shoes 30. Each of the dogs 29 and its associated shoe 30 constitute a feeding couple, and one of these feeding couples is so located as to be adjacent to each side 35 portion of the sheet, and are clearly illustrated in Figs. 3 and 4. The eccentrics 31 are mounted upon the stub shafts 33, while the eccentrics 32 are mounted on similar shafts 34 arranged, respectively, above and 40 below the surface of the feed table 26. The shafts 33 and 34 carry intermeshing spur gears 35 and 36, respectively, and the gear 36 of each feeding couple is in mesh with a spur gear 37 carried by a shaft 38 which 45 receives its power from any suitable source. By means of the eccentrics 31 and 32 a four-motion feed is imparted to the dogs 29 and shoes 30, that is to say, each of these elements moves toward the sheet, advances with 50 the sheet, moves away from the sheet, and then moves backwardly in analogy to the well known sewing machine feed. As the dogs and shoes move toward the sheet the latter is clamped between the same, and in 55 their advancing movement the sheet advances with them. It will be understood, of course, that the dogs and shoes operate at a sufficiently high speed to thus provide an intermittent feed for the sheets toward the 60 front guides 27 and into contact with the same. The engaging faces of the shoes 29 are longitudinally convex while the engaging faces of the shoes 30 are plane, whereby to facilitate the clamping of the sheet between these elements, and said shoes 30 are

also provided with rearwardly-extending guides 39 received by grooves 40, whereby the shoes 30 are held for movement in a straight line during their operation.

The side register of the sheet is effected by 70 means of a dog 41 and a shoe 42 (Fig. 5) constructed in all respects similar to the dogs 29 and the shoes 30, and coöperating with each other in the same way as the dogs 29 coöperate with the shoes 30. The shoe 42 75 is mounted upon an eccentric 43 carried by a stub shaft 44, which shaft also carries a miter gear 45 in mesh with a similar gear 46 carried by a stub shaft 47, and on said shaft 47 is a spur gear 48 which meshes with the 80 spur gear 37 of the feeding couple which is in closest proximity to said guide 28. The dog 41 is mounted upon an eccentric 49 carried by a stub shaft 50 having also mounted thereon a miter gear 51, and said gear 51 is 85 in mesh with a similar gear 52, the latter being carried by a stub shaft 53. The opposite end of the stub shaft 53 carries a miter gear 54 which meshes with a similar gear 55 mounted on a vertical stub shaft 56. At the 90 lower end of the shaft 56, is provided a miter gear 57 meshing with a similar gear 58, and said gear 58 is carried by the shaft 47. Through the train of gearing which has been just now described it will be seen that power 95 is communicated from the spur gear 37 to the dog 41 and the shoe 42, and these two elements have a four-motion feed the same as the dogs 29 and the shoes 30. They are positioned, however, to work in a line at right 100 angles to the line of movement of the dogs 29 and 30, and when the sheet is clamped between the dog 41 and the shoe 42 the same may be moved sidewise into contact with the side guide 28, and thereby effect side register 105 of the sheets.

The action of the feed dogs and shoes of the respective sets of feeding couples 29—30 and 41—42 is to present the sheets to the front and side guides 27 and 28, respectively, by acting in alternation on the sheet and thereby obtaining step by step front and side register of the sheet. When this has been effected they should be rendered inactive. It is proposed to accomplish this 110 through the medium of electroresponsive devices the actuation of which is controlled by the sheet itself. Each of the front guides has a circuit-closing switch lever or detector 59 pivotally mounted thereon, as at 60, 120 which lever controls an electrical circuit 61 wherein is included a source of current 62, such as a battery, and an electromagnet 63. The lever 59 coöperates with a fixed contact 64 connected to one leg of the circuit, the 125 other leg of the circuit being connected to the lever 59. The lower end of said lever 59 is in the path of movement of the sheet, and as said sheet advances its contact with lever 59 swings the same upon its pivot 60 so that 130

the upper end of the lever engages the fixed contact and closes the circuit at this point. The electromagnet 63 of each of the circuits 61 is thus energized each time the circuit is 5 closed at the contact 64, and correspondingly deenergized when the circuit is opened at this point. A similar circuit closing switch lever or detector 65 is also carried by the side guide 28, being pivotally 10 mounted thereon as at 66, and said lever 65 controls an electrical circuit 67 which includes a source of current 68, as a battery, and an electromagnet 69. The lever 65 is connected to one leg of said circuit 67, while 15 the other leg is connected to a fixed contact 70, the electromagnet 69 being energized when the lever 65 engages the contact point 70, and being deenergized when the circuit is opened at this point. It will thus be seen 20 that each of the circuits 61 and 67 is a localized circuit, operating independently of the other circuits, and being controlled by a make and break device independent of the make and break devices of the other circuits. 25

The shoes 30 and 42 are mounted for relative bodily movement toward and from their respective dogs 29 and 41. When moved from the dogs with which they coöperate, 30 the shoes 30 and 42 no longer exert a clamping action on the sheet, and the feeding couples are rendered inactive or non-feeding. This moving of the shoes 30 and 42 is effected by shifting their respective shafts 34 and 44, which shifting of the shaft 34 is accomplished by levers 71 pivotally mounted as at 72. A similar lever 73 pivotally mounted at 74 is connected to the shaft 44 of the shoe 42. The levers 71 and 73 are 35 actuated by the electromagnets 63 and 69, respectively, the armatures 75 of the electromagnets 63 being mounted on the levers 71, while the armature 76 of the electromagnet 69 is similarly mounted on the lever 73. 40 Each lever 71 carries a contact point 77 which coöperates with a fixed contact point 78, and the lever 73 has a contact point 79 which coöperates with a contact point 80. The contact points 77 and 78 and the 45 points 79 and 80 are all included in an electrical circuit 81, which also includes a source of current 82, such as a battery, and a plurality of electromagnets 83. The contact points are arranged in series relation to 50 each other, and until all of the contact points 77 and 79 are engaged with their respective fixed contacts 78 and 80, the circuit 81 will not be closed. It will be noted also that the electromagnets 83 are in series relation with 55 respect to each other; therefore, when the circuit 81 is closed these electromagnets are simultaneously energized.

As the sheet is fed forwardly and laterally over the feed table 26 it is brought into 60 contact with the circuit closing levers 59

and 65, respectively, and as each of these levers is swung upon its pivot under the movement of the sheet the circuits 61 and 67 are closed. This may occur practically simultaneously, or each of the circuits may 70 be closed at a slightly different time from the other circuits, but upon the energization of each of the electromagnets 63 and 69 their respective armatures will be attracted thereto, and the movable contacts 77 and 79 75 brought into engagement with the fixed contacts 78 and 80. As the levers 71 and 73 are thus swung on their pivots, the shoes 30 and 42 are moved slightly away from the dogs 29 and 41 with which they coöperate. The 80 feeding of the sheets thereby is stopped.

After the sheet has been registered at the last guide it is desirable that the same shall be retained in such position. A plurality of sheet-holding devices 84 is employed for this 85 purpose, each of said devices being provided with an engaging foot 85 designed to press against the sheet and hold the same on the feed table. The sheet-holding devices 84 are carried by a rod 86 suitably supported above 90 the feed table 26, and each of said devices 84 carries the armature 87 of one of the electromagnets 83. The armatures 87 should be of sufficient weight to hold the engaging feet 85 of the devices 84 normally elevated above 95 the feed table 26, and thereby permit passage of the sheet therebeneath, and when the electromagnets 83 are energized the attraction of the armatures by the electromagnets will force the engaging feet 85 downwardly 100 into clamped relation with the sheet, and thus hold the sheet in its registered position on the feed table. As before stated, the electromagnets 83 become active when the circuit 81 is fully closed by the instrumentalities hereinbefore described.

Each of the sheet-holding devices 84 carries a contact 88 which coöperates with a fixed contact 89, said contacts 88 and 89 being included in an electrical circuit 90 connected to a source of current 91, such as a battery, and in which circuit is also included a plurality of electromagnets 92. One of the electromagnets 92 is provided for each of the front guides 27, and the armature 93 110 of each of said electromagnets is connected to the front guide 27 with which said electromagnet is associated. The electromagnets 92 are arranged above the guides 27, and when they are energized their armatures 115 93 will be drawn upwardly, and the guides 27 thereby moved upwardly and out of the forward path of the sheet on the feed table 26. An electromagnet 94 is also provided for the side guide 28, being arranged in the 120 same relation thereto as the electromagnets 92 are arranged with relation to the front guides 27, said electromagnet 94 being also included in the circuit 90. The armature 95 of the electromagnet 94 is associated with 130

the side guide 28, and when said electromagnet 94 is energized it induces an upward movement in the side guide 28 by the attraction of the armature 95.

5 It will now be understood that when the sheet has moved to registered position its contact with the circuit-closing levers 59 and 65 renders the feeding couples inoperative. This is due to the actuation of the levers 71
 10 and 73 by the electromagnets 63 and 69. When this condition arises the circuit 81 is closed and the electromagnets 83 are energized. They act upon the sheet-holding devices 84 to clamp the sheet in engagement
 15 with the feed table, and thereby hold the sheet in its registered position. When this clamping action of the sheet-holding devices occurs the circuit 90 also becomes closed, the electromagnets 92 and 94 included therein
 20 become energized, and the front and side guides 27 and 28 are thereby moved upwardly and out of the path of movement of the sheet.

The sheet is now ready for presentation to
 25 the grippers of the impression cylinder 10. To effect this presentation the feed table 26 includes a plurality of under feed slides 96. With certain of these slides the sheet-holding devices 84 coöperate to retain the sheet
 30 in registered position, said sheet-holding devices being so mounted with respect to the slides 96 as to move therewith. At the under side of each of the slides 96 is provided a rack 97 engaged by a segmental gear 98,
 35 said gears being carried by a shaft 99 to which a rocker arm 100 is connected. The arm 100 is provided with a contact roller 101 which travels upon the face of a cam 102 associated with the impression cylinder
 40 10. During the rotation of the impression cylinder 10 the cam 102 actuates the arm 100 to rock the shaft 99 and the segmental gears 98 carried thereby, and this results in a reciprocation of the feed slides 96. On the
 45 forward movement of these slides 96 the front edge of the sheet is carried toward the impression cylinder 10, the grippers of the cylinder 10 being timed to engage the sheet and draw it forwardly from the slides 96.
 50 The slides 96 are then returned to their normal positions in the feed table 26.

It is essential that the several instrumentalities by which the operations last above described are accomplished shall remain set
 55 until the registered sheet has been taken by the grippers, otherwise there will be a premature restoration of these instrumentalities to their normal functioning positions. These instrumentalities are controlled by
 60 the switch levers 59 and 65 and their contacts 64 and 70 with which they coöperate. The levers and the contacts referred to, therefore, should be held in engagement until the registered sheet has been delivered to the
 65 grippers. For this purpose a holding dog

or detent 103 is provided for each of the levers 59, said detents being carried by a rock shaft 104, and a similar holding dog or detent 105, mounted upon a rock shaft 106 is provided for the switch lever 65 of 70 the side guide 28. The shafts 104 and 106 are connected for operation in unison by a pair of mitered gears 107 and said shafts are rocked by a tappet arm 108 adapted to be engaged by a stud or pin 109 carried by 75 the impression roll 10. The faces of the holding dogs 103 and 105 with which the levers 59 and 65 contact are beveled, so that as said levers ride up these beveled faces on the upward movement of the front and side 80 guides 27 and 28, respectively, the upper ends of said switch levers will be forced toward the stationary contacts with which they coöperate and held in engagement therewith. This maintains the circuits 61 85 and 67 closed while the front and side guides 27 and 28 are in their elevated positions; the several electromagnets remain energized, and only when the circuits are broken at the levers 59 and 65 and their contacts 64 and 70 90 will the electromagnets become deenergized. As the stud 109 engages the tappet arm 108 the latter is lifted with a resultant rocking of the shafts 104 and 106. This swings the holding dogs 103 and 105 away from the 95 switch levers 59 and 65, whereupon the latter separate from their respective fixed contacts, and the circuits 61 and 67 thereby become broken. The several electromagnets now become inactive; the levers 71 and 73 100 fall away from the electromagnets 63 and 69, restoring the shoes 30 and 42 to active relation with respect to their coöperating dogs 29 and 41, thereby restoring the feeding couples to active position; the sheet-holding devices 84 are raised to permit passage of the next succeeding sheet to be registered, and the front and side guides 27 and 28 move downwardly and in position to register the next sheet as it is advanced over 110 the feed table 26.

From the foregoing the operation of the herein described registering mechanism may be briefly summarized as follows: After each sheet leaves the stack 11 it is given a 115 preliminary side register by the rolls 15, the axes of which are arranged at an angle to the line of movement of the sheet, and by such movement the sheet is brought into contact with the side guide 16. The sheet is 120 then advanced to the feed table 26 where it encounters the intermittently-operating feeding couples made up of the dogs 29 and 41 and their coöperating shoes 30 and 42. These elements effect final front and side 125 register of the sheet bringing the same into contact with the front and side guides 27 and 28, whereupon the switch levers 59 and 65 are operated to close the circuits 61 and 67. This serves to render the feeding cou- 130

5 ples inoperative also; to clamp the sheet in engagement with the feed slides 96, and to raise the front and side guides 27 and 28; after which, the cam 102 being properly 10 timed to swing the arm 100, the guides 96 advance the front edge of the sheet so registered to the bite of the grippers for delivering the sheet to the impression cylinder. On the actuation of the tappet arm 108 the controlling circuits 61 and 67 are opened, and 15 the several instrumentalities are restored to their normal functioning relations to act upon the next succeeding sheet.

With the construction herein described operating in the manner set forth, it will be evident that greater accuracy of register is assured, due to the operation of the mechanism being dependent on the sheet itself. The sheet must contact each of the front and 20 side guides before the feeding couples are rendered inactive, and although the feeding couple controlled from a particular guide may cease its feeding action on the sheet by reason of the latter operating the circuit 25 closer of that guide, the sheet will not be clamped to the feed slides of the table, nor will the front and side guides be raised to permit passage of the sheet to the impression roll, until the sheet operates the circuit 30 closers of all the guides. This occurs only when both front and side register of the sheet has been attained.

It will be understood that while the angularly disposed feed rolls 15 are illustrated 35 as arranged to effect side register of the sheet against a side gage 16 at the left hand side of the path of sheet travel, side register at the right hand edge of the sheet may be substituted, if desired, by reversing the obliquity of the rolls as to center line of travel 40 either by shifting the rolls in their frame or by turning the frame of rolls over, a corresponding shifting of the side gage being likewise effected, or a duplicate of the side 45 gage 16 being provided on the right hand side of the frame.

I claim:

1. In a printing press, the combination 50 with a normally stationary feed table, of means for effecting thereon register of a sheet including a guide, means for engaging the sheet to feed the same over the table to said guide, means automatically to permit the operation of the feeding means when 55 registration has been secured, and means to move the table to deliver the registered sheet.

2. In a printing press, the combination 60 with a normally stationary feed table, of means for effecting thereon register of a sheet including a guide, means for engaging the sheet to feed the same over the table to said guide, means controlled by the sheet for rendering the feeding means inoperative 65 when register of the sheet has been effected,

and means to move the table to deliver the registered sheet.

3. In a printing press, the combination with a normally stationary feed table, of means for effecting thereon front register of 70 a sheet and including a front guide, means for intermittently engaging the sheet to feed the same to said guide, and means for rendering the feeding means inoperative when register of the sheet has been effected. 75

4. In a printing press, the combination with a normally stationary feed table, of means for effecting thereon front register of 80 a sheet and including a front guide, means for intermittently engaging the sheet to feed the same to said guide, and means for rendering the feeding means inoperative when register of the sheet has been effected, means to clamp the registered sheet to the table, and means to move the table and clamped 85 sheet to deliver the sheet and simultaneously to release the same from the clamping means.

5. In a printing press, the combination with a normally stationary but movable feed table, of means for effecting thereon register 90 of a sheet including a guide, means for engaging the sheet to feed the same over the table to said guide, means for clamping the registered sheet to the table to preserve the register thereof, and means for moving the 95 table to deliver the sheet while held in registered position.

6. In a printing press, the combination with a normally stationary feed table, of means for effecting on said table register of 100 a sheet including a guide, means for engaging the sheet to feed the same over said table to said guide, means for holding the sheet stationary relative to the table for preserving the register of the sheet, and means controlled by the printing couple for moving 105 the table and presenting the registered sheet while held in registered position on the table.

7. In a printing press, the combination 110 with a normally stationary feed table, of means for effecting on said table register of a sheet including a guide, means for engaging the sheet to feed the same over said table to said guide, means for rendering the 115 feeding means inactive when register of the sheet has been effected, means for holding the sheet stationary relative to the table for preserving the register of the sheet, and means controlled by the printing couple for moving 120 the table and presenting the registered sheet while held in registered position on the table.

8. In a printing press, the combination of 125 means for effecting front register of a sheet including a guide, a four-motion feeding device acting intermittently upon the sheet for advancing the same to said guide, and means associated with the guide for rendering said four-motion feeding device inoperative when register of the sheet has been effected. 130

9. In a printing press, the combination of means for effecting front register of a sheet including a guide, a four-motion feeding device for advancing the sheet step by step to said guide, and means associated with said guide and controlled by said sheet for rendering said feeding device inoperative when register of the sheet has been effected.

10. In a printing press, the combination of means for effecting register of a sheet including a front guide, means for intermittently engaging opposite sides of the sheet to feed the same step by step to said guide, means for imparting a four-motion feed to said engaging means, and means for rendering said feeding means inoperative when register of the sheet has been effected.

11. In a printing press, the combination of means for effecting side and front register of a sheet including guides, continuously acting means for intermittently engaging the sheet to feed the same step by step forwardly and laterally to said guides, and means for automatically rendering said feeding means inoperative when register of the sheet has been effected.

12. In a printing press, the combination of means for effecting front register of a sheet including a guide, feed dogs arranged above the plane of the path of movement of the sheet and adapted to engage the upper surface of the sheet, shoes arranged below the plane of the path of the sheet and adapted to engage the underside of the sheet, means for intermittently effecting engagement of said dogs and shoes with the sheet to advance the latter to said guides, and means for rendering said dogs and shoes inoperative when register of the sheet has been effected.

13. In a printing press, the combination of means for effecting front register of a sheet including a guide, feeding couples adapted to engage the sheet for advancing the same step by step to said guides, said feeding couples each including a dog and a shoe arranged at opposite sides of the sheet and adapted to intermittently engage the same, and means for rendering said feeding couples inactive when register of the sheet has been effected.

14. In a printing press, the combination of means for effecting front register of a sheet including a guide, feeding couples adapted to engage the sheet to advance the same step by step to said guide, each of said feeding couples including a feed dog and a shoe arranged at opposite sides of the path of movement of the sheet and adapted to clamp the sheet to advance the same toward the guide, means for imparting a four-motion movement to said dogs and shoes, and means for rendering the feeding couples inactive when register of the sheet has been effected.

15. In a printing press, the combination

of means for effecting front register of a sheet including a guide, means for feeding the sheet to said guide, means for holding the sheet in registered position, and means controlled by the sheet for controlling the action of said feeding and holding means.

16. In a printing press, the combination of means for effecting front register of a sheet including a vertically movable guide, means for feeding the sheet to said guide, means for holding the sheet in registered position, means for raising said guide to permit delivery of the registered sheet and means controlled by the sheet for controlling the action of said feeding, holding and guide-operating means.

17. In a printing press, the combination of means for effecting front and side register of a sheet including front and side guides, means for intermittently advancing the sheet to said front guide, means operating at right angles to the sheet advancing means to intermittently feed the sheet to said side guide, and means associated with the front and side registering means controlled by the sheet for rendering the sheet-advancing and side-feeding means inactive when front and side register of the sheet has been effected.

18. In a printing press, the combination of means for effecting front and side register of a sheet including front and side guides, intermittently operating feeding means for advancing the sheet to said front guide, intermittently operating feeding means for presenting the sheet to said side guide, the side feeding means operating at right angles to the movement of the sheet advancing means, means for rendering the sheet advancing and side feeding means respectively inactive independently of each other when front and side register of the sheet respectively has been effected, and means for delivering the registered sheet.

19. In a printing press, the combination of means for effecting front register of a sheet including a guide, means for effecting side register of the sheet and also including a guide, feeding couples for advancing the sheet step by step to said front guide, a feeding couple operating at right angles to the sheet advancing feeding couples for feeding the sheet step by step laterally to said side guide, and means associated with the front and side guides controlled by the sheet for rendering said feeding couples inactive independently of each other when front and side register of the sheet has been effected.

20. In a printing press, the combination of means for effecting front register of a sheet including a front guide, means for effecting side register of the sheet and including a side guide, means for advancing the sheet to said front guide, means operating at right angles to said advancing means for feeding the sheet laterally to said side

- guide, means associated with the front and side guides controlled by the sheet for rendering the sheet-advancing means and the side-feeding means respectively inactive independently of each other when front and side register of the sheet has been effected, and means actuated after register has been effected to deliver the sheet.
21. In a printing press, the combination of means for effecting front register of a sheet including a front guide, means for effecting side register of the sheet including a side guide, means for feeding the sheet to said front guide, means operating at right angles to said feeding means for feeding the sheet laterally to said side guide, means for holding the sheet in registered position, and means controlled by the sheet for rendering the respective sheet-feeding means inactive and for actuating the sheet holding means when front and side register of the sheet has been effected.
22. In a printing press, the combination of means for effecting front register of a sheet including a front guide, means for effecting side register of the sheet including a side guide, said front guide being vertically movable, means for feeding the sheet to said feeding means for feeding the sheet laterally to said side guide, means for holding the sheet in registered position, means controlled by the sheet for rendering the respective sheet-feeding means inactive and for actuating the sheet holding means when front and side register of the sheet has been effected, and means for raising said front guide to permit delivery of the registered sheet, said sheet-controlled means also rendering active said guide raising means.
23. In a printing press, the combination of means for effecting front register of a sheet including a front guide, means for effecting side register of the sheet including a side guide, independent feeding means for respectively advancing the sheet to said front guide and imparting to the sheet a lateral feed to said side guide, means for holding the sheet in registered position, means for actuating said front and side guides to permit delivery of the registered sheet to the impression roll, sheet controlled means for rendering said feeding means inactive, said sheet controlled means also serving to render active the sheet holding means and the guide operating means, and means for delivering the registered sheet.
24. In a printing press, the combination of means for effecting front and side register of a sheet including front and side guides, intermittently operating feeding means for advancing the sheet step by step to said front guide, and intermittently operating feeding means for presenting the sheet step by step to said side guide, the longitudinal and lateral feeding means arranged to act alternately upon the sheet.
25. In a printing press, the combination of means for effecting front and side register of a sheet including front and side guides, intermittently operating feeding means for advancing the sheet step by step to said front guide, intermittently operating feeding means for presenting the sheet step by step to said side guide, the longitudinal and lateral feeding means arranged to act alternately upon the sheet, means associated with the front and side guides for rendering the longitudinal and lateral feeding means respectively inactive independently of each other when front and side register has been effected respectively, and means for delivering the registered sheet.
26. In a printing press, the combination of means for forwarding the sheet and effecting preliminary side register including a side gage and a plurality of obliquely disposed driven feed rollers traversed by the sheet and means acting on the sheet thereafter to effect final register.
27. In a printing press, the combination with means for forwarding the sheet and effecting preliminary front and side register including front and side gages and a plurality of driven rollers traversed by the sheet and obliquely disposed relatively to the center line of sheet travel, and means acting on the sheet thereafter to effect final front and side register.
28. In a printing press, the combination of means for forwarding the sheet and effecting front and side register including front and side gages and a plurality of driven rollers traversed by the sheet and obliquely disposed relatively to the center line of sheet travel, an endless carrier provided with grippers arranged to take the sheet after register and a retarding suction roll for the trailing sheet end.
29. In a printing press, the combination of means for forwarding the sheet and effecting preliminary front and side register including front and side gages, and a plurality of driven rollers traversed by the sheet and obliquely disposed relatively to the center line of sheet travel, an endless carrier provided with grippers arranged to take the sheet after preliminary front register, a retarding suction roll for the trailing sheet end, and means to effect final side and front register of the sheet and to deliver the sheet.
30. In a printing press, the combination with means for effecting preliminary sheet register and comprising a stationary side guide, a removable front guide, a forwarding table arranged to shift the sheet toward the side guide as it approaches the front guide, and means to remove the front guide from the path of the sheet after preliminary

- front and side register is secured, of a feed table to receive the preliminarily registered sheet, front and side guides, feed devices to advance the sheets to the guides to effect final register, means to render the sheet feeding devices inoperative as and when final register is secured, and means to advance the table to deliver the finally registered sheet thereon to the printing couple.
31. In a printing press, the combination with means for effecting preliminary sheet register and comprising a stationary side guide, a removable front guide, and a forwarding table consisting of a series of parallel rolls extending at an angle of slightly less than ninety degrees to the side guide and arranged to shift the sheet toward the side guide as it approaches the front guide, and means to remove the front guide from the path of the sheet after preliminary front and side register is secured, of a movable but normally stationary feed table to receive the preliminarily registered sheet, front and side guides, feed devices to advance the sheets to the guides to effect final register, means to render the sheet feeding devices inoperative as and when final register is secured, and means to advance the table to deliver the finally registered sheet thereon to the printing couple.
32. In a printing press, the combination with means for effecting preliminary sheet register and comprising a stationary side guide, a removable front guide, a forwarding table consisting of a series of parallel rolls extending at an angle of slightly less than ninety degrees to the side guide and arranged to shift the sheet toward the side guide as it approaches the front guide, and means comprising a Geneva gear to remove the front guide from the path of the sheet after preliminary front and side register is secured, a conveying device provided with grippers to take the preliminarily registered sheets and deliver the same from the forwarding table, of a feed table to receive the preliminarily registered sheet, front and side guides, feed devices to advance the sheets to the guides to effect final register, means to render the sheet feeding devices inoperative as and when final register is secured, and means to deliver the finally registering sheet to the printing couple.
33. In a printing press, the combination with means for effecting preliminary sheet register and comprising a stationary side guide, a removable front guide, a forwarding table consisting of a series of parallel rolls extending at an angle of slightly less than ninety degrees to the side guide and arranged to shift the sheet toward the side guide as it approaches the front guide, and means to remove the front guide from the path of the sheet after preliminary front and side register is secured, an endless conveyer and gri-

pers thereon to take the preliminarily registered sheets, and a suction device to further advance the sheet when released by said grippers, of a feed table to receive the preliminarily registered sheet, front and side guides, feed devices to advance the sheets to the guides to effect final register, means to render the sheet feeding devices inoperative as and when final register is secured, and means to deliver the finally registered sheet to the printing couple.

34. In a printing press, the combination with means for effecting preliminary sheet register and comprising a stationary side guide, a removable front guide, a forwarding table consisting of a series of parallel rolls extending at an angle of slightly less than ninety degrees to the side guide and arranged to shift the sheet toward the side guide as it approaches the front guide, and means to remove the front guide from the path of the sheet after preliminary front and side register is secured, of a normally stationary feed table to receive the preliminarily registered sheet, front and side guides, feed devices to advance the sheets to the guides to effect final register, means to render the sheet feeding devices inoperative as and when final register is secured, means brought into action concurrently with the stoppage of the feeding and acting to clamp the registered sheet to the feed table, and means to advance the feed table together with the clamped sheet to deliver the finally registered sheet to the printing couple.

35. In a printing press, the combination with means for effecting preliminary sheet register and comprising a stationary side guide, a removable front guide, a forwarding table consisting of a series of parallel rolls extending at an angle of slightly less than ninety degrees to the side guide and arranged to shift the sheet toward the side guide as it approaches the front guide, and means to remove the front guide from the path of the sheet after preliminary front and side register is secured, of a normally stationary feed table to receive the preliminarily registered sheets, front and side guides, feed devices to advance the sheets step by step to the guides and effect final register, means controlled by the sheets to render the sheet feeding devices individually inoperative as and when final register is secured of that portion of the sheet acted upon by the respective feeding devices, means brought into action concurrently with the stoppage of the feeding and acting to clamp the registered sheet to the feed table, and means to advance the feed table together with the clamped sheet to deliver the finally registered sheet to the printing couple.

36. In a printing press, the combination with means for effecting preliminary sheet register and comprising a stationary side

guide, a removable front guide, a forwarding table consisting of a series of parallel rolls extending at an angle of slightly less than ninety degrees to the side guide and arranged 5 to shift the sheet toward the side guide as it approaches the front guide, and means to remove the front guide from the path of the sheet after preliminary front and side register is secured, of a normally stationary feed 10 table to receive the preliminarily registered sheets, front and side guides, feed devices to advance the sheets step by step to the guides and effect final register, means controlled by the sheets to render the sheet feeding devices 15 individually inoperative as and when final register is secured of that portion of the sheet acted upon by the respective feeding devices, said last named means comprising

detector elements associated with the guides and forming switches for electric circuits 20 including magnets operatively connected with said sheet feed devices, means controlled by said detectors and the circuits and brought into action concurrently with the stoppage of the feeding and acting to clamp the registered sheet to the feed table, and means to advance the feed table together with the clamped sheet to deliver the finally registered sheet to the printing couple.

In testimony whereof I have hereunto 25 signed my name in the presence of two subscribing witnesses.

CARL HENDERSON.
